(57) **CLAIM**

The ornamental design for a reflected-light table lamp, as shown and described.

DESCRIPTION

FIG. 1 is a perspective view of a reflected-light table lamp embodying our design;

FIG. 2 is an end elevation view as seen from the left side of FIG. 1;

FIG. 3 is a front elevation view thereof;

FIG. 4 is a rear elevation view thereof;

FIG. 5 is a top plan view thereof; and

FIG. 6 is a bottom plan view thereof.

FIG. 7 is a front elevation view of a reflected-light table lamp showing a second embodiment of the design, the sole difference being the appearance and shape of the reflector.

FIG. 8 is a front elevation view of a reflected-light table lamp showing a third embodiment of the design, the sole difference being the appearance and shape of the reflector; and,

FIG. 9 is a front elevation view of a reflected-light table lamp showing a fourth embodiment of the design, the sole difference being the appearance and shape of the reflector.
